FRUIT-SIZING MACHINE.

1,385,218.

Specification of Letters Patent. Patented July 19, 1921.

Application filed April 16, 1919. Serial No. 290,440.

To all whom it may concern:

Be it known that I, ALLEN H. MCINTYRE, a citizen of the Dominion of Canada, and a resident of Dunedin, in the county of Pinellas and State of Florida, have invented a new and Improved Fruit-Sizing Machine, of which the following is a full, clear, and exact description.

The object of the present invention is to provide a machine particularly adapted for sizing peaches and similar fragile fruits, in which a relatively slow operating machine shall have a relatively large capacity and in which the fruit shall be gently supported, transported and separated into lots of substantially uniform size, without the liability of bruising and injuring the fruit.

To the above ends the invention consists of the fruit sizing machine and the devices and combinations of devices as shown in the accompanying drawings and as hereinafter described and claimed.

In the drawings I have shown a fruit sizing machine embodying the invention, in which similar reference characters indicate corresponding parts.

Figure 1 shows a longitudinal sectional view through the machine, parts being shown in elevation and the section being taken on the line 1—1 in Fig. 2.

Fig. 2 is a broken top plan view.

Fig. 3 shows in partial top plan and sectional view portions of the sizer or conveyer.

Fig. 4 shows in partial sectional view and partial side elevation portions of the sizer or conveyer.

Fig. 5 shows a broken view of portions of the sizer or conveyer and the tracks for supporting and controlling the operation thereof, parts being shown in transverse section.

The machine comprises a suitable supporting frame 10 which may be of any suitable construction, of sufficient strength and rigidity to support the operative parts, but which need not be particularly described, and obviously it can be made of any desirable material such as wood or iron.

In the machine as illustrated the sizer consists of a sizing conveyer, two parallel endless sprocket chains 16, which are supported and driven by the sprocket wheels 15, mount-

ed upon shafts 11, 12, 13 and 14, suitably supported in journals in the frame 10.

The chains 16 travel in a fixed path about the sprocket wheels, and in order to insure the proper support and guidance of the upper run of the chains 16 and the sizing conveyer, suitable tracks 17 are provided extending between the sprocket wheels 15 carried by the shafts 11 and 12, which tracks (see Fig. 5) may be trough-like structures fixed to the inner faces of the vertical uprights of the frame 10 in any suitable manner, with the openings facing inward toward each other, the lower sides of the trough supporting the chain 16, and the upper sides slightly over-lapping the sizer as clearly shown in Fig. 5. This construction will permit parts of the sizer to drop below the guides 17, while preventing any upward movement above the path of travel, and as shown the path of travel from left to right will be slightly upward.

The inner opposing links of the chains 16 at suitable intervals and the required distance apart, are provided with inwardly projecting trunnions 18, upon which are supported, so as to be freely revolved, the rollers 19 (see Figs. 3, 4 and 5). As the trunnions 18 are carried by the chains 16, the rollers 19 are caused to work in the fixed path of movement of the chains 16.

The trunnions 18 also support, so as to freely swing thereon, the links 22 which at their free ends are provided with inwardly projecting trunnions 21, upon which are mounted to freely revolve rollers 20, the rollers 19 and 20 extending across the machine from side to side between the chains 16 and 90 are arranged in pairs spaced apart and parallel to each other.

The foregoing construction is such that the rollers 19 and 20 of each unit may freely revolve, and while at all times retaining a fixed distance with relation to each other, yet the roller 20 of each pair of rollers 19 and 20 has an up and down swinging movement with the pivoted links 22 about the trunnions 18 as a center, and into and out of the path of movement of the chains 16 and the rollers 19 carried thereby, thus the roller 20 of one unit has an up and down movement with relation to the roller 19 of an adjacent unit.

This up and down movement of the rollers 20 varies the width of the opening between the rollers 20 of one pair of rollers 19 and 20, of one unit and the rollers 19 of an adjacent unit for a purpose to be hereinafter described.

The pivoted links 22 and the rollers 20 carried thereby fall by gravity, as they pass from the left-hand or entering end of the 10 machine, as the machine is shown in Fig. 1, toward the right-hand end; the direction of movement being indicated by the arrow in Fig. 1, and the rollers 20 rest upon and pass over suitable tracks 25 and 26 as indicated 15 in Fig. 1, the tracks 25 being fixed to the vertical supports of the frame in any suitable manner and at a slightly varying distance from the plane of movement of the chains 16, from the left-hand toward 20 the right-hand end; in other words, the tracks 17 and 25 and 26 diverge slightly, so as to widen the space between them from the left-hand toward the right-hand end.

From the tracks 25, as the sizing conveyer 25 passes toward the right, as shown in Fig. 1, the rollers 20 will pass to and are supported by adjustable tracks 26, forming a continuation of tracks 25.

These adjustable tracks 26 are supported 30 by threaded bolts 27 (see Fig. 4) by means of which they may be adjusted up and down with relation to the guides 17 and the path of travel of the chains 16 and rollers 19, so as to regulate the distance to which the 35 rollers 20 may drop, with relation to the path of movement of the rollers 19, and thus regulate the movement of the rollers 20 of one unit, with relation to the rollers 19 of the next adjacent unit. Preferably the 40 tracks 26 at the extreme right-hand end will be sharply deflected downward as shown in Fig. 1.

From the foregoing description it will be observed that as the sizing units pass from 45 the sprocket wheels 15 mounted on the shaft 11, toward the right, the rollers 20 of each unit will drop by gravity below the path of travel of the chains 16 and the rollers 19, and that the distance between the roller 20 50 of one unit and the roller 19 of the next adjacent unit will be gradually increased and the space widened, as the conveyer moves toward the right, until the roller 20 passes off of the right-hand ends of the tracks 26, 55 at which time they will drop so that the roller 20 will be directly beneath the roller 19 of its unit.

Further travel toward the right brings the rollers 20 into engagement with tracks 60 70^a by means of which the rollers 20 of each unit are raised, so that when they pass about the sprocket wheels 15 on the shaft 12, they be restored to the plane of movement of and will follow directly behind the 65 rollers 19, in the same line of movement.

From the sprocket wheels 15 on the shaft 12 the sizing conveyer passes to the inclined support 71, and about the sprocket wheels 15 on the shaft 13, to the inclined support 72, and thence about the sprocket wheels 70 15 on the shaft 14 and thence over the inclined support 60; the rollers of each unit as the sizing conveyer passes downward in contact with the support 71 and upward in contact with the support 72, and thence over 75 the support 60, being positioned directly in line with each other and traveling in the same path of movement.

The fruit to be sized is delivered to the upper surface of the sizing conveyer and 80 comes to rest in the space between the rollers 19 of one unit and the rollers 20 of the next adjacent unit, and in order to prevent the fruit from coming to rest between the rollers 19 and 20 of a single unit, the space between these rollers will be closed by a guard 85 23, extending transversely across and substantially closing the space between the rollers 19 and 20 of a given unit, between the links 22.

Preferably these guards 23 will be supported by pins 24, carried by the links 22, and their opposite edges will be curved to conform to the curvature of the rollers 19 and 20, but will be out of contact therewith, 90 so as not to interfere with the free rolling action of the said rollers, and the upper surfaces of the guards 23 will be disposed in a plane parallel to a line drawn to touch the peripheries of the rollers, as clearly 95 shown in Figs. 3 and 4.

These guards are not shown in Figs. 1 and 2, and in Fig. 2 other parts of the machine below the sizing conveyer, have been omitted for the sake of clearness of illustration. 105

The guards 23 constitute an effectual means for preventing the fruit from resting in the space between the rollers 19 and 20 of a unit, and insure that any fruit which 110 may drop thereon when delivered to the sizing conveyer, or which may have come to rest thereon at the initial point of introduction of the fruit thereto, will, as the sizing conveyer moves from the left toward the right, as the machine is shown in Fig. 1, fall by gravity until it comes to rest in the space between the roller 19 of one unit and the roller 20 of the next adjacent unit, ready to be released and discharged as the space 115 between such rollers is widened, by the dropping of the rollers below the path of travel of the rollers 19.

From the foregoing description it will be understood that the fruit delivered to the 125 upper surface of the sizing conveyer will, regardless of its size, come to rest upon the rollers 19 and 20 of adjacent units, and will be carried along and slowly revolved as the rollers 20 are revolved by contact with their 130

supporting tracks 26, until the dropping of the rollers 20 shall have widened the space between the rollers 19 and 20 of adjacent units, sufficiently to permit a given size fruit 5 to pass through the opening, and as the rollers 20 gradually drop lower and lower, as the sizing conveyer is moved, from the left-hand to the right-hand end of the machine, the space between the rollers 19 and 10 20 of adjacent units gradually becomes wider, and permits the passage through the openings, of fruit of gradually larger diameter.

It is of course essential that the fruit as 15 it is released by the sizer shall not be permitted to drop any great distance, and it is further essential that it be divided up into lots, the fruit in any one lot approximating a given size within particular limits of variation, which of course is determined to a great extent by the number of lots into which the fruit will be separated and divided. If divided into two lots as it falls 20 from the sizer, the variation in size in such lots will be considerably greater than if divided into four lots or a larger number of lots.

In the machine of the drawing, I have shown means whereby the fruit as it is released and falls from the sizing conveyer will be divided into four lots; thus the fruit which is released as the sizing conveyer passes over the tracks 25, will be received upon deflectors 30 and 31 located closely adjacent to the under surface of the tracks 25, and finally rolls upon a transversely running endless belt 32, which carries the fruit and delivers it to a trough 33.

Obviously the fruit delivered by the sizing conveyer to the belt 32, will be of the smallest range of sizes as the distance between the tracks 25 and the path of movement of the chains 16 and the rollers 19, while varying somewhat from the left-hand 45 to the right-hand end of the tracks 25, is considerably less in this section of movement of the sizing conveyer than at any other point, in the upper run of the sizing conveyer, so that the spaces between the rollers 20 of one unit and rollers 19 of adjacent units, will be relatively narrower, permitting the release of the fruit of the smaller diameters.

As the sizing conveyer passes on to the tracks 26, the space between the rollers 20 of one unit and the rollers 19 of an adjacent unit gradually gets larger and larger, from the left-hand to the right-hand end of such tracks, permitting gradually larger diameters of fruit to be released, and by adjusting the tracks 26, with relation to the line of movement of the chains 16 and the rollers 19, the width of the openings between the rollers 19 and 20 of adjacent units 60 65 may be regulated, as required by the range

of sizes of any particular lot of fruit being run through the machine.

Beneath the tracks 26, there is located a transversely running belt 42, upon which the fruit is deposited as it is released by the sizing conveyer; the belt 42 being mounted upon and driven by suitable pulleys and supporting and carrying the fruit laterally from under the sizing conveyer, and delivering it between guiding partitions 40, and 41, and deflecting partitions 52, and 53, leading to the troughs 45, 46 and 47, and as there are two partitions dividing the surface of the belt into three sections, obviously the fruit delivered to the belt 42 beneath the tracks 26, will be divided into three lots, the fruit in each lot being substantially uniform, but of slightly varying diameters within a given range.

Obviously the number of partitions may be varied to reduce or increase the number of lots into which the fruit delivered by the sizing conveyer may be divided, and in order to control the range of size of any given lot or lots, the partitions 40 and 41 are adjustable, so they may be positioned at different points transversely to the width of the belt 42, and beneath, and with relation to the tracks 26.

For this purpose the partitions 40, and 41, are provided with slots 48, engaged by bolts 49, fitted and adjustable in slots 50, of the slotted supports 51, attached to the frame.

Any suitable means may be provided, as for instance the bolts 49, for effecting this adjustment of the partitions 40 and 41.

It will of course be understood that while it is preferable to provide for an adjustment of the tracks 26, an efficient machine may be produced, by simply providing diverging tracks for the chains 16 and rollers 19, and the rollers 20 respectively, permitting the gradual widening of the space between the rollers 19 and 20 of adjacent units, without such adjustment of the tracks 26, by simply adjusting the position of the partitions 40 and 41 across the width of the belt 42, or by using a greater or lesser number of such partitions, to separate the fruit into given lots, as it is released by the sizing conveyer.

The fruit to be separated and sized will be delivered to the upper surface of the sizing conveyer, as it passes over the support 60, and just about as it is to pass on the tracks 25, and preferably the fruit will be 120 delivered in rows, extending transversely across the sizing conveyer.

For this purpose a delivering conveyer 55 is employed, (see Fig. 1), which may and preferably will consist of a pair of sprocket 125 chains passing about suitable sprocket wheels, and driven by any suitable mechanism, and preferably at a speed one-half of that of the sizing conveyer, and such delivering conveyer 55 comprises rollers car- 130

ried by sprocket chains as indicated in Fig. 1.

As this delivering conveyer 55 moves at a speed one-half that of the sizing conveyer, 5 a row of fruit will be delivered approximately between the rollers 19 and 20 of adjacent units.

It will of course be understood that the relative position of the parts will be such 10 that the fruit will be delivered from the delivering conveyer 55, to the sizing conveyer, without the necessity of dropping it any great distance, so as to be deposited gently upon the rollers 19 and 20, and that such 15 fruit as may fall upon the guards 23, will drop in line with the fruit in the space between the rollers 19 and 20 of adjacent units, and that this lining up of the fruit will be greatly facilitated by the rolling action of 20 the rollers 19 and 20, with the fruit resting thereagainst and thereon, as the sizing conveyer travels from left to right.

By sharply depressing the discharging ends of the tracks or supports 26 the space 25 between the rollers 19 and 20 of adjacent units, will be enlarged to the maximum extent, to insure the discharge from the sizing conveyer of all the fruit upon the surface of the belt 42, before any given unit passes 30 from the track 26.

It will of course be understood that suitable guards and guides will be provided where necessary, to insure that the fruit shall not roll laterally from the sizing conveyer, or from the belts 32 and 42, or in its 35 passage to the troughs 33, 34, 45, 46 and 47.

As shown in Fig. 1 the bottoms of the troughs 45, 46 and 47 will be slightly inclined so that the fruit will roll by gravity 40 to the outer ends thereof in convenient position for the packers.

It will of course be understood that the delivering conveyer 55, and the sizing conveyer will be driven by power from any 45 suitable source. If desired, however, the sizing conveyer may be provided with a crank 82, on the shaft 12 by means of which it may be operated by hand.

It is to be observed that the separation of 50 the fruit in my machine is accomplished by the gradual gravitational movement of one of a pair of supports with relation to the adjacent support and according as the space between the supports increases in width, and 55 that such increase in width and the movement of the movable support with relation to the fixed support is controlled by diverging tracks or guides which gradually permit the movable support to fall below the 60 fixed support, and that such relative movement of the supports is not dependent upon any positively operating instrumentalities, whereby to move them.

It will be further noted that where piv- 65 otal swinging units are used, by providing

for a gradual falling of the free end of one unit, with relation to the pivotal point of the next adjacent unit, I provide for a gradual widening of the space, without a sudden movement of parts dependent upon 70 tripping levers and other instrumentalities, thus insuring that the fruit supported by the rollers of adjacent units, will be released and discharged as soon as the opening therebetween becomes wide enough to 75 permit the release and discharge of fruit of a diameter corresponding to the width of the space between adjacent units.

The operation of my machine has been sufficiently set forth in connection with the 80 foregoing description of its construction and organization, and I deem a further description of its operation to be unnecessary to those skilled in this art.

It is to be particularly noted that the sizing, separation and the delivery of the fruit to the various troughs in the present machine is accomplished by providing two parallel transversely extending supports spaced apart normally a distance less than the diameter of the smallest fruits to be sized and separated, and that the fruit rests upon the supports over the space between them and that one of the supports moves in a fixed path while the other, while moving in the 95 same general direction, also has a movement below the path of movement of the adjacent supports and that this downward movement of the movable support takes place under the force of gravity and the 100 limit of movement is controlled by a track or guide diverging in the direction of longitudinal movement from the track or path of travel of the fixed support or the vertical movable support, the result being that the 105 space between the two supports is progressively widened during the lateral movement so as to release the fruit of varying diameters at different points along the line of travel, and so far as I am aware of the prior 110 state of the art, such sizing and separating instrumentalities embodying a gravitationally movable support for operating with a relatively fixed support has not heretofore been employed in machines of this character.

I prefer to employ freely rotating rollers for the supports, but obviously my invention is not limited thereto nor is it limited to the exact details of construction which have been illustrated in the drawings and described in the foregoing specification.

Having described my invention, I claim:

1. In a fruit sizing machine, in combination, a sizing conveyer, means to move the 125 sizing conveyer in a substantially horizontal plane, said sizing conveyer comprising two laterally extending parallel spaced fruit supports, one of said supports being movable below, and out of and into the path of 130

- travel of the sizing conveyer and with relation to the other support.
2. In a fruit sizing machine, in combination, a sizing conveyer, means to move the sizing conveyer in a substantially horizontal plane, said sizing conveyer comprising two laterally extending parallel spaced fruit supports, one of said supports being movable below, and out of and into the path of travel of the sizing conveyer and relatively to the other support, and independent tracks for supporting and controlling said supports.
3. In a fruit sizing machine, in combination, a sizing conveyer, means to move the sizing conveyer in a substantially horizontal plane, said sizing conveyer comprising two laterally extending parallel spaced fruit supporting rollers, one of the said rollers being movable below, and out of and into the path of travel of the sizing conveyer, and relatively to the other roller.
4. In a fruit sizing machine, in combination, a sizing conveyer, means to move the sizing conveyer in a substantially horizontal plane, said sizing conveyer comprising two laterally extending parallel spaced fruit supporting rollers, one of the said rollers being movable below, and out of and into the path of travel of the sizing conveyer, and relatively to the other roller, and independent tracks for supporting and controlling the said rollers.
5. In a fruit sizing machine, in combination, an endless sizing conveyer, comprising parallel endless chains, a fruit support extending laterally and connected to said chains, a fruit support pivotally connected to said chains, and arranged parallel to the first support and spaced apart therefrom, and an inclined track supporting and controlling the movement of the pivoted support with relation to the fixed support.
6. In a fruit sizing machine, in combination, a sizing conveyer, comprising endless chains, parallel transversely extending fruit sizing rollers supported by said chains, one of said rollers being pivotally connected to said chains and having a movement into and out of the path of travel of said chains and with relation to the other roller, and a track or support controlling the movement of said pivoted roller.
7. In a fruit sizing machine, in combination, a sizing conveyer, comprising a plurality of transversely extending fixed fruit sizing rollers, and a plurality of pivotally connected fruit sizing rollers, horizontally arranged and extending parallel to and spaced apart from the fixed rollers, and independent tracks for supporting and controlling the path of movement of the fixed rollers and the pivotally connected rollers, said pivotally connected rollers being movable into and out of the path of travel of the fixed rollers.

8. In a fruit sizing machine, in combination, a sizing conveyer, comprising a pair of endless chains, a plurality of fixed parallel fruit sizing rollers supported by said chains and extending transversely across the machine, swinging links connected to said chains and interposed between and alternating with said fixed rollers, fruit sizing rollers supported by the free ends of the said swinging links in position to extend parallel to the fixed rollers, guards carried by said links, and an adjustable track or support to control the extent of the swinging movement of said links and the roller carried thereby, with relation to the fixed rollers.
9. In a fruit sizing machine, in combination, a sizing conveyer, means to move the sizing conveyer in a substantially horizontal plane, said conveyer comprising two laterally extending parallel spaced fruit sizing supports, one of the said supports being movable below, and out of and into the path of travel of the sizing conveyer and relatively to the other support, and an adjustable track or support for controlling the relative movement of the movable fruit sizing support.
10. In a fruit sizing machine, in combination, a sizing conveyer, means to move the sizing conveyer in a substantially horizontal plane, said conveyer comprising two fruit sizing supports, one of the said supports being movable below, and out of and into the path of travel of the sizing conveyer and relatively to the other support, means to control the relative movement of the movable support, and adjustable guiding and separating partitions located beneath the sizing conveyer and adjustable along the path of travel thereof.
11. In a fruit sizing machine, in combination, a sizing conveyer comprising endless chains, transversely extending fixed fruit sizing supports carried by the said chains, movable fruit sizing supports pivotally connected to and swinging below, and into and out of the plane of travel of said chains and fixed supports, and movable guides and tracks controlling the swinging movement of the swinging supports, to cause said swinging supports to travel in the path of the fixed supports at substantially all points excepting along that portion of travel where said sizing conveyer receives, supports and sizes the fruit, with means to permit the swinging supports to gradually move below the path of travel at this portion of the machine.
12. A fruit sizing machine, in combination, a sizing conveyer comprising endless chains, fixed fruit sizing rollers extending transversely across and supported by the said chains, swinging links pivotally connected at one end to the said chains, fruit sizing rollers carried by the said links at their opposite ends, said rollers being ar-

ranged parallel to the fixed rollers and alternating therewith, means to support and drive the said chains and rollers in a substantially horizontal plane, fixed diverging 5 independent tracks for controlling the relative movement of said rollers along a portion of their travel, and an adjustable track located below the fixed track for controlling the relative movement of said rollers during 10 a portion of their travel, and forming a continuation of the diverging tracks.

13. In a fruit sizing machine, in combination, a sizing conveyer comprising a substantially horizontally movable carrier, a 15 plurality of parallel fruit sizing supports extending transversely across said carrier, pivotally connected swinging fruit sizing supports interposed between and relatively movable below, and into and out of the 20 plane of movement of the carrier and the fixed supports, means to control said swinging supports and to limit the extent of their movement, and a delivering conveyer for delivering the fruit in transversely extending 25 rows to the sizing conveyer.

14. In a fruit sizing machine, in combination, a sizing conveyer comprising a substantially horizontally movable carrier, a plurality of parallel fruit sizing supports 30 extending transversely across said carrier, pivotally connected swinging fruit sizing supports interposed between and relatively movable below, and into and out of the plane of movement of the carrier and the fixed 35 supports, means to control said swinging supports and to limit the extent of their movement, a delivering conveyer for delivering the fruit in transversely extending rows to the sizing conveyer, and means to move 40 the delivering conveyer at a relatively slower speed than that at which the sizing conveyer is moved.

15. In a fruit sizing machine, in combination, a sizing conveyer comprising endless 45 chains supported and driven so that the upper reach shall be in a substantially horizontal plane, and comprising a plurality of transversely extending fruit sizing supports secured to said chains and movable with and 50 in the plane thereof, a plurality of alternating movable fruit sizing supports extending transversely and parallel to the fixed supports, and a track or guide therefor extending along a portion of the horizontal reach, 55 permitting and controlling the movement of the movable supports below, and out of and into the plane of travel of the fixed supports.

16. In a fruit sizing machine, in combination, a sizing conveyer, means to move the 60 sizing conveyer in a substantially horizontal line in one direction, means for receiving the fruit discharged from the conveyer located beneath the conveyer and relatively close thereto, fruit supporting and discharging 65 instrumentalities carried by the con-

veyer, and means to operate the same to lower the fruit toward the receiving means and to discharge the fruit in a direction opposite to that in which the conveyer is moving. 70

17. In a fruit sizing machine, in combination, a sizing conveyer comprising a pair of fruit sizing rollers extending transversely across the machine and arranged parallel to each other and spaced apart normally a 75 distance less than the diameter of the average fruit being operated upon, one of the rollers being movable downwardly and away from the other roller so as to gradually widen the space between the rollers, and so means to move the conveyer to effect the movement of the movable roller.

18. In a device of the class described, a conveyer embodying spaced grading elements and movable grading elements mounted to 85 swing in arcs and coöoperating with the spaced grading elements to define grading openings; and means for progressively lowering the movable grading elements to vary the size of the said grading openings. 90

19. In a device of the class described, a conveyer embodying spaced grading elements and movable grading elements coöperating with the spaced grading elements, the movable grading elements being mounted to swing in arcs and to rotate on their axes; and means for progressively lowering the movable grading elements to vary the distance between the spaced and movable grading elements, the movable grading elements coöperating with said means thereby to impart rotation to the movable grading elements. 100

20. In a device of the class described, a conveyer comprising main grading elements 105 having straight line advancing movement with the conveyer and auxiliary grading elements having advancing movement with the conveyer and radial swinging movement on the conveyer toward and away from the main grading elements to define grading openings; and means coöperating with the auxiliary grading elements to vary the size of the said grading openings. 110

21. In a device of the class described, a 115 conveyer comprising main and auxiliary grading elements disposed in pairs, the auxiliary grading element of each pair being suspended on the conveyer for radial swinging movement toward and away from the main grading element of an adjoining pair; and means for adjusting the auxiliary grading elements with respects to the main grading elements.

22. In a sizer and grader, a conveyer comprising main rollers, and auxiliary rollers movable toward and away from the main rollers to define grading openings of different sizes; and tracks whereon the lower portion of the main and auxiliary rollers rest to 130

impart rotation to the main and auxiliary rollers in the same direction when the conveyer is advanced.

23. In a sizer and grader, a conveyer comprising main rollers, and auxiliary rollers movable toward and away from the main rollers to define grading openings of different sizes; tracks whereon the lower por-

tions of the main and auxiliary rollers rest to impart rotation to the main and auxiliary 10 rollers in the same direction when the conveyer is advanced; and means for raising and lowering the track of the auxiliary rollers.

ALLEN H. McINTYRE.
